tion of Delaware

Application May 27, 1937, Serial No. 144,997

3 Claims. (Cl. 201—55)

This invention relates to a variable or adjustable resistance of the type especially adapted for employment as a volume or tone control instrumentally in radio receivers, and to a method of making such a resistance.

One of the objects of the invention is to provide a variable resistance of this character which is much smaller and far more compact and more closely organized than previously known devices of this character and yet is as equally effective as the larger devices heretofore made, known, or used. In particular, the variable resistance embodying the present invention has maximum dimensions approximately one-half those of devices heretofore known and yet has the capacity and effectiveness of similar devices twice its size.

In carrying out the invention the resistance element is so constituted as to be capable of standing up under the maximum amount of heat generated by virtue of the passage of current therethrough and yet is combined in such a novel manner with its metal casing that although the resistance element is electrically insulated from the casing it is in good or efficient heat interchanging relation therewith and the casing itself is constituted to aid in the dissipation of the heat transmitted thereto from the resistance element. In the performance of its function of dissipating the heat, the casing may be and preferably is aided by the mounting bushing and the structure on which it is supported.

The invention further proposes a novel type of adjustable or rotatable contact constituted so as to be radially resilient and otherwise adapted for effective cooperation with the carbonaceous coating or conductive surface of the resistance element. The adjustable contact is combined with its operating shaft and with a stop arrangement in a simple and effective manner. The invention also provides a novel way of insulating and mounting the terminals and electrically connecting them with the ends of the resistance element.

In its various embodiments the invention provides one type of structure in which the adjustable or rotatable contact element is directly connected to its operating shaft and consequently it, as well as the resistance, is electrically connected to the casing and its bushing, and also another type of structure wherein the adjustable contact and the resistance are electrically insulated from the metal housing and its bushing, provision being made in the latter instance for the simple and advantageous connection of

the adjustable contact in the circuit in which the device is incorporated or with which it is associated.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a plan view on an enlarged scale of a variable resistance embodying the present invention of the type in which the adjustable contact is directly fixed to its operating shaft, parts being broken away for the sake of illustration;

Figure 2 is a sectional view taken on line 2—2 of Figure 1, parts being shown in elevation for the sake of illustration;

Figure 3 is a detail view in top plan showing the stop plate combined with the operating shaft;

Figure 4 is a similar detail view of the adjustable or rotatable contact;

Figure 5 is a view in bottom plan showing the insulating cover plate, its terminals and the contact arms associated with the terminals;

Figure 6 is a view similar to Figure 1 but showing an embodiment of the invention in which the adjustable contact is electrically insulated from its operating shaft and therefore from its bushing and the housing or casing;

Figure 7 is a sectional view taken on line 7—7 of Figure 6;

Figure 8 is a view in top plan showing the adjustable contact employed in the embodiment of the invention shown in Figures 6 and 7;

Figure 9 is a view in bottom plan of the cover plate and terminal arrangement utilized in the form of the invention shown in Figures 6 and 7;

Figure 10 is a detail view in top plan of the stop plate employed with this form of the invention;

Figure 11 is a fragmentary view on an even greater enlarged scale taken partly in transverse section and partly in elevation and illustrating the manner in which the resistance element is combined with the metal casing;

Figure 12 is a diagrammatical view partly in side elevation and partly in longitudinal vertical section showing a machine which may be employed for assembling the resistance elements with their casing; and

Figure 13 is a fragmentary view partly in section and partly in perspective showing a different

way of combining the resistance element with the metal housing or casing.

The embodiments of the invention shown in Figures 1 to 11 are illustrated on a scale four times their actual size to clarify the illustration and make the drawings easier to read. The two embodiments of the invention shown in Figures 1 to 11 have certain features in common and these will first be described. In both of these embodiments the variable resistance comprises a metal casing or housing designated generally at 1 and having a cylindrical wall or body portion 2, and an end wall 3 integral with one end of the cylindrical wall 2. The other end of the cylindrical wall 2 is open. The end wall 3 is provided with a central opening to receive an end portion of an externally threaded bushing 4. The end of the bushing adjacent the wall 3 of the housing is provided with an outwardly directed and integral annular flange 5. This flange 5 is secured to the end wall of the housing in any suitable way but preferably by projection welding, that is to say, small, inwardly extending projections are provided on the end wall 3 adjacent its central opening and these projections are fused or melted down under pressure and the influence of a heavy welding current. By welding the parts together in this manner, the bushing is effectively secured to the housing and an efficient heat interchanging connection is established therebetween. The same result could be obtained by machining or stamping the housing and its bushing out of one piece, and to some extent the advantages may be had by staking the bushing to the housing in the conventional fashion, but preferably the parts are separably formed and welded together in the manner described.

To the inner curved wall of the body portion 2 of the metal housing a resistance element designated generally at 6 is applied. The resistance element 6 is made up of a thin strip of dense heat resisting paper (about .005" to .007" thick) which paper, due to its density, has better than the average thermal conductivity of ordinary paper although able to stand up under the heat conditions to which it is subjected. A suitable paper for this purpose is the so-called armature slot paper that is treated "rag base" paper commonly used for insulating the conductors of electrical machines in their slots. A resistance coating of carbonaceous material is applied to one surface of this paper, preferably in the so-called tapered resistance manner, well known in the art, to meet the resistance variations required to get the desired volume control or tone control in a radio receiver. Interposed between the resistance element 6 and the inner curved wall of the body portion 2 of the metal housing is a layer of electrically insulating but heat conducting adhesive 7. This layer 7 may take the form of a coating or film or it may be a thin strip.

The length of the resistance strip or element 6 is such that when assembled with the housing, there is a gap between its adjacent ends. The adhesive layer is however continuous and unbroken throughout the angular or circumferential extent of the inner curved wall of the body portion 2 of the casing and is somewhat wider than the resistance element 6 to prevent the possibility of current leakage to the metal case.

Due to the enlarged scale on which the drawings are made, the adhesive insulating layer 7 appears to be of some substantial thickness. Ac-

tually the layer 7 is quite thin, so much so that the effect so far as heat conduction is concerned is practically the same as though the resistance element were in direct contact with the inner wall of the housing. Of course, however, there is sufficient of the insulating adhesive layer 7 to electrically insulate the resistance element 6 from the metal case.

The invention may be carried out by coating the inside walls of the housing with a suitable adhesive, such as an insulating japan, and when this is in a semi-dry or tacky condition the resistance element is curled with its resistance coating on the concave inner surface of the cylindrical wall of the body portion 2 of the metal housing thereby causing it to adhere to the insulating coating of japan. Further drying and baking of the japan coating by suitably controlled means will then cause the resistor to adhere firmly to the curved inner wall of the housing with a minimum thickness of insulating material between the wall of the housing and the resistance surface.

Another way of combining the resistance element with the casing consists in coating the inner surface of the housing with a solution of a thermo-plastic resin or equivalent adhesive which is allowed to dry completely before inserting the resistance element. After the resin has dried, a strip of the resistance material is curved to conform to the inner cylindrical wall of the housing and its uncoated surface is pressed, by an expandable plug, firmly against the film or layer of the resin or adhesive while the housing is heated to a temperature sufficient to soften the thermo-plastic coating and cause adherence and intimate contact between the resistance element and the adhesive coated wall of the housing. Here again, while the resistance element is securely held in position it is electrically insulated from the metal housing and yet in good heat interchanging relationship thereto.

Another and preferred way of combining the resistance element with the housing is to interpose a thin strip of thermo-plastic resin or a thin piece of paper impregnated with said resin between the uncoated surface of the resistance element and the inner wall of the housing, the interposed strip being slightly wider and larger than the resistance element to insure effective electric insulation. When the resistance element, strip and casing or housing are assembled in the manner described the resistance element is pressed firmly against the strip and the strip against the inner wall of the housing by means of an expanded plug while the housing is heated sufficiently to cause softening of the thermo-plastic strip and consequent intimate adhesion of the resistance element to the metal housing.

The present invention proposes to heat the thermo-plastic strip or film to its softening point by heating the walls of the metal housing just long enough to effect the desirable heating of the thermo-plastic strip or film without heating the resistance element itself to any appreciable extent. Excessive heating of the resistance element is likely to cause a change in its resistance. To avoid this and at the same time obtain rapid production the present invention proposes to heat the strip by exposing the assembly of the casing, strip and resistance element to a high frequency electromagnetic field for a short time. In other words, the well known high frequency electrical induction method of heating is adapted to effect this operation. 75

In Figure 12 an apparatus for carrying out this mode of heating the assembly is diagrammatically illustrated.

The apparatus shown in Figure 12 comprises a base 10 on which a carrier plate 11 is slidably supported, the carrier plate being constrained by suitable guides or ways to slide back and forth across the base 10 and having its movement in either direction limited by stop pins 15 and 16. On the carrier plate 11 are a pair of similar holders designated at 12 and 13. These holders are of identical construction and each is provided with a vertically extending central opening in which a hollow pin 14 is fitted, each pin 14 projecting down into an opening provided therefor in the carrier plate 11. An assembly of the casting 1, bushing 4, thermo-plastic strip 7 and resistance element 6 is mounted in the holder engaged with either the stop pin 15 or 16, the bushing 4 of the unit extending down into the hollow pin 14 thereof as shown in Figure 12. In the example illustrated in Figure 12 the assembly just referred to has been first associated with the holder 12. The carrier plate 11 is then slid over until the holder 13 engages the stop pin 16, and the holder 12 with the assembly mounted thereon is disposed beneath and in vertical alignment with the pilot 20 of the ram 21 of a press. The ram of the press is then lowered by manipulation of a conventional foot pedal (not shown) until the rubber plug 22 guided by the pilot 20 extending into the bushing 4 presses the resistance element 6 and also the insulating strip 7 against the inner wall of the body portion 2 of the casting 1 with a maximum pressure determined by spring and stop (not shown) in the press. Simultaneously with the lowering of the ram 21 a circuit is closed by spring supported contacts (not shown) coacting with the ram of the press. These contacts when closed permit electric current from a high frequency generator (not shown) to pass through the flexible leads 23 to an induction heating coil 24 for a time which is accurately determined by the heating of a timing device (not shown) on the magnetic switch (not shown) which controls the high frequency generator. While this operation is being completed on the unit in one holder (the holder 12 in Figure 12) the operator mounts another unit in the holder 13 which at this time is not under the ram of the press. Since the time required to complete the heating of a unit is only a second or so this cycle of operation makes for maximum production. It will be noted that the radial pressure exerted by the rubber plug 22 results from the pressure exerted on it by the conical surfaces 25 and 26 formed on the lower end of the ram 21 and on the flange 27 of the pilot 20, the plug being interposed between these conical surfaces and the pilot 20 being supported for limited sliding movement in the bore of the ram.

As previously indicated the high heat dissipation resulting by thus mounting the resistance in intimate thermal relation with although electrically insulated from the metal case makes it possible to reduce the size of the metal casing of the resistance to approximately one-half of that formerly used for the same electrical load. This brings the diameter of the unit capable of dissipating one watt or more down to five-eighths of an inch.

A hollow operating shaft 30 is supported for rotation in the bushing 4 in the embodiments of the invention shown in Figures 1 to 10, the shaft 75 in each instance being limited in its inward

movement by means of a split annular spring washer 31 snapped into an annular groove 32 provided in the shaft and engageable with the outer end of the bushing. The inner end of the shaft is employed in each instance to rotate the movable contact, but as the structure from this point on in these two embodiments differs, their remaining elements will be separately described.

In the structure shown in Figures 1 to 5 the movable contact is designated generally at 35 and has a disk-like body portion 36 having its inner periphery notched as at 37 to adapt it to interlock with the inner end of the operating shaft 30 when the inner end portion is staked into engagement with the movable contact and with its cooperating stop plate 38 which is disposed inwardly of the movable contact. The stop plate 38 has similar notches 37' for the same purpose.

Integral with the disk-like body of the movable contact is a spring contact member 39 in the form of an approximately U-shaped loop with the ends of the loop merging into the peripheral portion of the body of the movable contact and the bite of the loop shaped to present a contact pad 40.

This construction, while simple and readily and inexpensively fabricated supplies the movable contact 35 with resiliency required and well adapts it in other respects for use with a unit of this type. The pad 40 of the movable contact in the assembly has wiping contact with the carbonaceous coating or conductive surface of the resistance. Between the underside of the body portion 36 of the movable contact 35 and the adjacent flanged end of the bushing 4 suitable washers designated at 41 and 41' are interposed. By staking the inner end of the shaft in the movable contact 35 and its stop plate 38 these parts are permanently secured to the shaft and are constrained to rotate therewith. The stop plate 38 has a radial projecting lug 42 which is engageable with a cooperating stop lug 43 which may be conveniently struck up from the end wall 3 of the metal case. These lugs limit the rotation of the movable contact in either direction and prevent its contact pad 40 from riding off either end of the resistance element.

The end wall 3 of the metal case may have an insulating washer 44 applied thereto.

The open end of the metal case is closed by a disk-like cover 45 of insulating material, the cover being held in place by tabs 46 which may be integral with the body portion of the metal case and be bent over the circular edge of the cover as shown in the drawings. In this form of the invention the cover 45 carries two of the terminals designated at 47 and 48. The third terminal 49 may be integrally formed with the case in this embodiment of the invention since the movable contact and consequently the resistance element are not insulated from the operating shaft but are electrically connected to this shaft and consequently to the bushing 4 and case 1.

The terminals 47 and 48 are of identical construction although oppositely arranged. Each includes a slotted portion 50 projecting externally of the cover and formed at the outer end of an inclined intermediate portion 51 which extends through slots 52 in the cover and has a flat inner portion 53 integral therewith, disposed on the inner side of the cover and riveted thereto as at 54. Integral with the flat portions 53 are curved contact arms 55, the ends of which are shaped and adapted to bear flush against the end portion of the carbonaceous coating or conductive

surface of the resistance element 6. They are, however, located above and out of the path of travel of the contact pad 40 and adjacent portions of the movable contact.

5 In the form of the invention shown in Figures 6 to 10 inclusive the movable or rotatable contact associated with the inner end of the operating shaft 30 is designated generally at 60. It has an approximately disk-shaped body portion 10 61 having a lateral extension 62 with which a curved contact member or arm 63 is integrally formed. The portion of the arm 63 engageable with the resistance is curved or bowed as at 63' to provide a contact pad or button. The body portion 15 61 of the adjustable contact rests flatly on an insulating washer 64 and is interconnected thereto so as to be constrained to rotation therewith by means of lugs 65 integral with the body portion and extended at right angles therefrom 20 and into peripheral notches 66 formed in the insulating washer 64. The insulating washer 64 has notches 66' on its inner periphery to receive the displaced portions 67 of the inner end of the shaft which is staked into engagement with its 25 insulating washer and with a similarly notched stop plate 68. The stop plate 68 is disposed on the opposite side of the washer 64 from the adjustable contact 61. A washer 69 is interposed between the stop plate 68 and the adjacent 30 flanged end 5 of the bushing 4. The stop plate 68 has a stop lug 70 which is cooperable with a stop lug 71 struck up from the end wall 3 of the case or housing. These stop lugs 70 and 71 function to limit the angular rotation of the 35 shaft and adjustable contact in either direction. It will be noted that while the shaft is staked into mechanical engagement or interlocking relationship with the washer 64 and the stop plate 68 it is spaced from the adjustable contact 60 and is electrically insulated from this contact 40 by the insulating washer 64.

A cover plate 72 of insulating material is provided for the open end of the casing in this form of the invention and as in the other structural type is held in place by tabs or lugs 73 integral with the body portion 3 of the casing and bent over the periphery of the cover plate in the assembly.

50 Terminals 47' and 48' are carried by and combined with the cover plate 72. These terminals 47' and 48' are identical with the terminals 47 and 48 previously described and are combined with their cover plate in exactly the same manner in which the terminals 47 and 48 are combined with their cover plate 45. These terminals 55 47' and 48' have contact arms 55' corresponding to the contact arms 55 and cooperable with the resistance element 6 in just the same way as the contact arms 55.

55 In the Figures 6 and 7 the casing is shown as 60 having a third terminal 49 integral therewith because the casing shown is identical in the two embodiments of the invention shown in Figures 1 to 11. However, in the embodiment shown in 65 Figures 6 to 10 this third terminal 49 has no useful function and may be dispensed with. An active or effective third terminal designated at 75 is provided and is supported on the insulating cover 72, the terminal 75 being riveted to the cover 72 by means of a rivet 76. An angular portion 77 of the third terminal 75 extends through a slot 78 provided in the cover plate 72 and its inner extremity is bifurcated and provided with contact buttons 79 which bear or wipe 75 against the body portion 61 of the movable con-

tact 60. By supporting the third terminal and the adjustable contact in an insulating manner and electrically connecting them in the manner shown and described, the adjustable contact may be conveniently incorporated in or associated with 5 an electric circuit while being insulated from the operating shaft, its supporting bushing, and the metal case or housing.

The construction shown in Figures 6 to 10 provides a fully insulated potential divider or potentiometer type of resistance such as are most commonly used in radio circuits.

Figure 13 illustrates a specifically different way of combining or positioning the resistance element in the casing of a variable resistance of the 15 type here under consideration.

In Figure 13 the casing is designated at 80 and has a cylindrical wall 81 and an integral end wall 82. A bushing 83 is suitably combined with the end wall 82 and resistance and provides the support for the operating shaft 84. A spring contact arm 85 is fixed to the inner end of the shaft 84 and its outer end is connected to a contact member 86 which wipes against a resistance element 87. This resistance element 87 consists of a thin 25 strip of paper of flexible material of the character previously described and provided on its upper or exposed face with a conductive coating such as a coating of carbonaceous material. An adhesive layer of the character previously described and designated at 88 is interposed between the resistance element and the end wall 82 of the casing. In this case we have a flat annular resistance element and it is applied to the end wall 30 instead of the curved or cylindrical wall of the 35 casing or housing. As in the other embodiments of the invention this resistance element although electrically insulated from the case by the adhesive layer is so intimately related thereto as to be in adjacent heat interchanging relation with 40 the case.

With this type of structure a flat circular platen of a press will serve to stick the resistance and adhesive layer firmly to the metal end or bottom of the case while the latter is heated by suitable means to secure the desired assembly and interrelation of the parts.

45 From the foregoing it will be understood that the present invention involves a novel method of combining a resistor with a metal case and while 50 the method may be carried out in the various ways above described, in each instance it contemplates placing a resistor in the case with the uncoated surface of the resistance strip adjacent the inner metal wall of the case and with the 55 carbonaceous coated or conductive surface of the strip facing inwardly. Interposed between the uncoated surface of the resistance strip and the adjacent wall of the metal case is a layer of electrically insulating but heat conductive adhesive, 60 as described, which may take various forms. With the parts of the resistance thus assembled the resistor or resistance strip is pressed outwardly toward the adjacent wall of the housing and the housing is heated to soften the thermoplastic resin or other adhesive with the result that the resistor is caused to adhere firmly to and have intimate thermal-conductive relation with the wall of the metal casing although electrically insulated therefrom. In this way rapid dissipation 65 of heat from the resistor is insured and the electrical load capacity of the resistor is increased.

70 While I have shown and described several constructions in which the variable resistance con- 75

stituting the present invention may be embodied and illustrated also several methods of making the resistance, it is to be understood that these particular descriptions are in many respects illustrative only and that various forms and modifications within the spirit of the invention and the scope of the subjoined claims are contemplated as will be apparent to those skilled in the art.

The invention claimed is:

- 5 1. A variable resistance of the character described comprising a metal casing having a curved wall, a resistor comprising a thin strip of heat resistant material having a conductive coating on one side thereof, said resistor being curved 10 to conform to the curved inner wall of said casing with the coating exposed to the inside of the housing, said resistor being of such length as to provide a gap at the ends thereof when so placed, a thin electrically insulating adhesive layer 15 interposed between said strip and the metal wall and being co-extensive of said gap and causing the strip to adhere to the wall whereby the strip although electrically insulated from the wall is 20 in effective heat interchanging relationship therewith.
2. A variable resistance of the character described comprising a metal casing, a resistor comprising a thin base of good thermal-conductivity and a conductive resistance film on one side of 25 said base, said base being mounted with its uncoated surface adjacent an inner surface of said metal casing, a gap between the ends of said base, an electrically insulating adhesive of good ther-

mal-conductivity interposed between and cementing the uncoated side of the base to the surface of the metal casing to which said base is adjacent and covering the surface of said casing at said gap, and an externally threaded metal 5 bushing fused to a wall of the casing whereby the bushing as well as the metal casing takes part in the dissipation of the heat generated in the resistance by the passage of electric current therethrough and transmitted to the casing by 10 virtue of the good thermal conductivity of the electrically insulating adhesive.

3. A variable resistance of the character described comprising a metal casing, a resistance element directly applied to but electrically insulated from the inner wall of the casing, an operating shaft supported on the casing, an insulating washer secured to said shaft for rotation therewith, a movable contact having a circular portion interconnected with the washer for rotation therewith but electrically insulated from the shaft and having a curved contact member bearing against said resistance element, an insulating cover for said casing, a pair of terminals mounted on said cover and having contact arms 25 engageable with the ends of the resistance element, and a third terminal also supported on said insulating cover and having a bifurcated inner portion provided with contact pads bearing 30 against the circular portion of the movable contact.

ERWIN R. STOEKLE.
